UNITED STATES PATENT OFFICE.

FRANCIS A. RAMEY, OF WOODSTOCK, VIRGINIA, ASSIGNOR OF ONE-HALF
TO GEORGE W. KOONTZ, OF WOODSTOCK, VIRGINIA.

CAR-COUPING.

No. 817,001.

Specification of Letters Patent.

Patented April 3, 1906.

Application filed October 31, 1905. Serial No. 285,256.

To all whom it may concern:

Be it known that I, FRANCIS A. RAMEY, a citizen of the United States, residing at Woodstock, in the county of Shenandoah and State of Virginia, have made certain new and useful Improvements in Car-Couplings, of which the following is a specification.

My invention is an improvement in car-couplings; and it consists in certain novel constructions and combinations of parts, as will be hereinafter described and claimed.

In the drawings, Figure 1 is a perspective view of the entire coupling. Fig. 2 is a horizontal longitudinal section of the coupling. Fig. 3 is a longitudinal vertical section on the line 3 3 of Fig. 2. Fig. 4 is a vertical cross-section on the line 4 4 of Fig. 2. Fig. 5 is a perspective view of the oscillating section or head of the coupling. Fig. 6 is a perspective view of the main or body section. Fig. 7 is a perspective view of the locking-dog, and Fig. 8 is a perspective view of the carrier for the dog.

By my invention I seek to provide an oscillating draw-head section and devices for holding the coupling-knuckle in locked position when said section is in normal position and for releasing the locking devices for said coupling-knuckle when the oscillating section is moved laterally in either direction out of its normal position.

As shown, the draw-head A is formed with a main or body-section B and with an oscillating section C, and the main or body section B has a draw-bar D, which may be secured in any suitable manner to the framing of the car.

The body or main section B is provided with a top plate E and a bottom plate F, and the head is provided with grooves E' and F' in respectively their under and upper faces and with ribs e' and f' in advance of said grooves, forming a track curving from side to side and equally on opposite sides of the central line of the draw-head in which the section C oscillates in the operation of the invention. The section C is curved on its rear face to correspond with the curved front face B' of the section B, between its upper and lower plates E and F, such section C being provided on its upper side with a curved rib C' and on its lower side with a curved rib C'', said ribs operating in the ways formed in the body portion or main section, so the section C may

oscillate in the operation more fully described 55 hereinafter. The main section B is also provided in advance of its base-groove F' with cam-surfaces F³, inclining upwardly from a central depressed seat F⁴, in which the lower end of the carrier-bolt J, presently described, 60 rests when the automatic section is in normal position.

The center from which the curved rear end of the section C is formed is approximately in line with the line of draft on the pivoted 65 knuckle H of the section C, so that the draft strain exerted on the knuckle H will not tend to oscillate the section C in its curved bearing of the main section B, so that normally the draft on the section C will not release the locking devices, and the depressed seat F⁴ is so related to the lower end of the carrier-bolt J 70 that a limited swinging movement of the section C will not interfere with the locking devices presently described. 75

The knuckle H is pivoted at H' and is provided with a projecting tailpiece H², which when the knuckle is in coupled position swings into the mortise C³ in the front end of the section C and engages with and is held by 80 the locking devices, which I will now describe. These locking devices include the dog I and the carrier J for said dog. This carrier J is in the form of an upright bolt having at its lower end a foot-piece J', which rests normally in the seat F⁴ and rides upon the cam-surfaces F³ when the section C is oscillated 85 in one direction or the other. The upper end of the foot-piece J' forms a shoulder which engages beneath the dog I when the carrier J is raised or forced upwardly and releases said dog I from engagement with the tailpiece and permits the latter to swing forward, releasing the coupling-knuckle. The carrier J 90 extends above the draw-head and may be elevated by hand when it is desired to release the coupling and may also be elevated in case of an accident to release the coupling by the engagement of the lower end of said carrier with the cam-surfaces of the 95 draw-head, as before described.

The dog I is of a special construction, which I will now describe. The dog I operates within the mortise C³ and is provided with an opening I', through which the carrier J 100 passes, such opening being sufficiently large to permit the dog to rock slightly on the carrier J in a direction transverse to the direc- 105

tion of draft, so the dog may tilt to permit the passage of the tailpiece H^2 in the adjustment of the knuckle H to coupled position. As shown, the dog I is provided in its front face with a recess I^2 , whose upper wall i^2 is inclined so the engagement of the tailpiece H^2 with the dog will lift the same as the knuckle H adjusts to coupled position. The outer edge of the dog I at I^3 fulcrums on an abutment I^4 in the base-wall of the mortise C^3 in the tilting of the dog in the operation of the invention.

The base-wall of the recess C^3 is provided with an upwardly-projecting lug or portion K , which projects upwardly along the inner side of the dog I near the inner end of same and aids in bracing the dog and relieving the carrier J of the strain of the coupling when the tailpiece is engaged with the said dog at the front edge of the latter in the coupled position of the parts.

Means are provided for yieldingly holding the oscillating section C in alignment with the main section to prevent any accidental displacement of same. As shown, these comprise spring-operated means bearing on opposite sides of the section C and consisting, as shown, of plates L , extending at their front ends along the opposite sides of the section C and provided at their rear ends with inwardly-projecting portions L' , bearing against the draw-bar or other portion of the main section, a bolt L^2 being passed through the draw-head and plates L and bearing on its ends springs L^3 , pressing against the plates L , and nuts L^4 for regulating the tension of the springs. By this means the oscillating draw-head section will be held normally in alignment and yet can be forcibly moved in either direction when desired.

A spring M (see Fig. 2) operates to hold the knuckle normally in position for coupling. This is important, as by retaining the knuckle in position for coupling at all times I avoid the danger resulting from the necessity, in the absence of such spring, of going between the cars to set the knuckle.

As best shown in Figs. 1, 2, and 3, I provide what for convenience of reference I term a "king-bolt" N , being in the nature of a connecting-rod extending from end to end of the car and headed at its opposite ends at N' to engage with the oscillating coupling-head and extending thence through a slot N^2 , extending transversely from side to side of the back of said oscillating head, and thence through an opening N^3 in the draw-bar and engaged at N^4 by a draw-key operating in connection with the draw-bar, (see Figs. 2 and 3,) and operating to draw the oscillating head back against the main section of the draw-head, as will be understood from Figs. 2 and 3 of the drawings.

In operation it will be noticed that so long as the coupled cars are on the track and in

normal position the coupling devices will hold the cars coupled. If one of the cars should be turned over or thrown down an embankment or otherwise misplaced, it will shift the oscillating section to one side or the other and the carrier J will ride up on one or the other of the cams and lift the dog, releasing the tailpiece and permitting the coupling-knuckle to swing forward, thus preventing the derailment of all the cars of the train.

The construction is simple, easily operated, and will be found efficient for the purpose for which it is designed.

What I claim is—

1. The combination substantially as herein described, of the main draw-head section provided with a top plate, and a bottom plate, spaced apart and provided in their inner faces with grooves forming a track curving from side to side and equally on opposite sides of the central line of the draw-head, an oscillating section provided with ribs fitting in said grooves, a pivoted knuckle on said oscillating section and having a projecting tailpiece, a dog for securing said tailpiece, a carrier-bar for said dog having means for engagement with the dog, and a portion projecting downwardly below the oscillating section, and cams on the main portion of the draw-head on opposite sides of the central line thereof and adapted for engagement by said downwardly-projecting portion of the carrier-bar when the oscillating section is moved to one or the other side of a central line, and spring-operated devices for holding the oscillating section yieldingly in normal position, substantially as set forth.

2. A car-coupling having an oscillating draw-head section having a coupling-knuckle, devices for locking the coupling-knuckle in locked position when the oscillating section is in normal position, and means for automatically releasing said locking devices when the oscillating section is moved laterally in either direction out of its normal position.

3. The combination in a car-coupling, with the main or body section, and the oscillating section held thereto, of a king-bolt in the nature of a rod connection extending longitudinally through the main or body portion of the draw-head and engaged with the oscillating head, the latter being movable transversely across the king-bolt, substantially as set forth.

4. The combination in a car-coupling, with a main draw-head section, of a draw-head section oscillating bodily relatively to the main section and provided with coupling devices, means for locking the said coupling devices when the oscillating section is in normal position, and means for releasing the locking devices when the said section is shifted out of normal position, substantially as set forth.

5. The combination of the oscillating draw-

head section having a coupling-knuckle, the main draw-head section having cam-surfaces, a dog for locking the knuckle in coupled position, and means operated from the cams of the main section for releasing said dog.

5 6. The combination of the main draw-head section having curved ways, the oscillating section having means held in said ways whereby such section may be oscillated bodily in connection with the main section, coupling devices, devices for locking the coupling devices, and means for automatically releasing said locking devices when the oscillating section is shifted out of normal position.

15 7. The combination of the main draw-head section, the oscillating draw-head section, having coupling means, devices for locking said means in coupled position when the oscillating section is in normal position, spring-operated devices for holding the oscillating section yieldingly in normal position, and means for releasing the locking devices by the lateral movement of the oscillating section.

25 8. The combination of the main draw-head section, the oscillating draw-head section, having a knuckle provided with a tailpiece, the dog for securing the tailpiece, the carrier for releasing said dog, and cams on the main draw-head section for operating said carrier, substantially as set forth.

30 9. The combination of the main draw-head section, the oscillating draw-head section, having a knuckle provided with a tailpiece, the dog fitting loosely in the oscillating section and having an inclined surface for engagement by the said tailpiece, and a carrier for bodily shifting the dog to release the tailpiece substantially as set forth.

35 10. The combination of the main draw-head section provided with ways curving

from side to side for the oscillating section and having in advance of its lower way a depressed seat for the carrier-bar, and cams on opposite sides thereof, the oscillating draw-head section having means operating in the 45 ways of the main draw-head section and provided with a knuckle having a tailpiece, a dog for securing said tailpiece and a carrier for said dog, resting normally in the seat of the main draw-head section and arranged to 50 engage with the cams on opposite sides thereof, when the oscillating section is shifted from normal position, substantially as set forth.

11. A car-coupling comprising a main 55 draw-head section, an oscillating draw-head section provided with coupling devices and oscillating bodily in the main draw-head section, means for locking the coupling devices in coupled position when the oscillating section is in normal position and means for releasing the said locking means when the oscillating section shifts out of normal position substantially as set forth.

12. The combination of the main draw-head section, the oscillating draw-head section, provided with a coupling-knuckle, devices for locking the said knuckle in coupled position in the normal position of the oscillating section, means for releasing the said locking devices when the oscillating section is moved laterally out of normal position, and spring-operated devices for holding the oscillating section yieldingly in normal position, substantially as set forth.
